UNITED STATES PATENT OFFICE.

GEORGE H. KNIGHT, OF PROVIDENCE, RHODE ISLAND, ASSIGNOR TO WILLIAM R. LANE & CO., OF SAME PLACE.

ORNAMENTAL RING FOR JEWELRY.

SPECIFICATION forming part of Letters Patent No. 404,092, dated May 28, 1889.

Application filed October 27, 1888. Serial No. 289,330. (No model.)

To all whom it may concern:

Be it known that I, GEORGE H. KNIGHT, a citizen of the United States, residing at Providence, in the State of Rhode Island, have invented a new and useful Improvement in Ornamental Rings for Jewelry, of which the following is a specification.

The nature of my invention consists in a ring formed from a double-plated seamless tube, having the base metal at its ends concealed by turning a thin flange of the tube over the same, as hereinafter fully set forth.

Figure 1 represents an axial section of a piece of double-plated seamless tubing from which the ring is to be formed. Fig. 2 represents the same with a portion of its periphery at each end cut away to form a thinned flange for turning against the base metal at the end of the tube to conceal the same. Fig. 3 represents a section of a double-plated seamless tube, which is cut away interiorly to form the concealing-flange. Fig. 4 represents a section of the finished ring, in which the concealing-flange, as shown in Fig. 2, has been turned outward. Figs. 5, 6, and 7 are enlarged detail sections showing the form of the flange and the method of turning the same against the base metal at the end of the tube. Figs. 8 and 9 represent a section of a seamless tube formed of several concentric tubes, from which my improved plated ring can be formed.

In the accompanying drawings, A, Fig. 1, represents a seamless tube provided with an exterior plated surface, *a*, and interior plated surface, *b*, the said tube being readily formed from double-plated sheet-metal stock in suitable dies; and in order to provide the tube A with a plated end I first remove a peripheral portion of the tube at each end to form the thinned flanges *c c*, which are beveled at their outer edge, as shown in Figs. 2 and 5; or instead of removing an external portion of the tube to form the flanges *c c* the required portion may be removed from the interior of the tube, as shown in Fig. 3, thus forming the flanges *c' c'*, which are to be turned inwardly

in order to properly cover the base metal, *d*, at the ends of the tube. The flanges *c c* (shown in Fig. 2) are to be first turned outwardly, as shown in Fig. 6, and then the beveled edge *g* 50 of the flange turned inward, so as to completely cover the base metal, *d*, with the plating *b*, as shown in Figs. 4 and 7.

When the ring is completed, as shown in Fig. 4, the plating *b* of the inner side of the ring will be extended over the end *e* of the tube, thus covering the base metal, *d*, and will abut closely against the edge of the plating *a* of the outer surface of the ring, as also shown enlarged in Fig. 7.

The jointless plated ring so formed will stand the test of dipping in acid, and will have all the appearance of a solid gold ring, the burnished seams *ff*, where the plated surfaces of the interior and exterior of the ring 65 are made to join, being readily made impervious to the acid.

Instead of forming the ring from a seamless tube A in one piece, two seamless tubes, A' A'', arranged one within the other, can be employed, as shown in Fig. 8, the tube A' being plated upon its outer surface and the tube A'' upon its inner surface only.

An intervening tube, A''', entirely of base metal, may also be employed in order to make 75 a ring of extra thickness, as shown in Fig. 9.

I claim as my invention—

A jointless ring having plated inner and outer surfaces, and having the base metal at the edge of the ring concealed by means of 80 a flange which is beveled at its end, and turned so that the plating of the flange will be carried over the edge of the ring and over the base metal at the end of the flange, and be made to abut edge to edge with the plating of the opposite surface, substantially as 85 described.

GEORGE H. KNIGHT.
